(57) **CLAIM**

The ornamental design for a pedestal light assembly, as shown and described.

DESCRIPTION

FIG. 1 is a front perspective view of a pedestal light assembly;

FIG. 2 is a bottom perspective view of the pedestal light assembly;

FIG. 3 is a front view of the pedestal light assembly;

FIG. 4 is a right side view of the pedestal light assembly;

FIG. 5 is a rear view of the pedestal light assembly;

FIG. 6 is a left side view of the pedestal light assembly;

FIG. 7 is a top view of the pedestal light assembly;

FIG. 8 is a bottom view of the pedestal light assembly; and,

FIG. 9 is a front perspective view of the pedestal light assembly in a collapsed configuration.

The broken line depictions form no part of the claimed design.
